UNITED STATES PATENT OFFICE.

JOSEPH BOERO, OF PARIS, FRANCE, ASSIGNOR TO GARDNER CRUSHER COMPANY, A CORPORATION OF NEW YORK.

DISINTEGRATOR.

1,013,527.

Specification of Letters Patent.

Patented Jan. 2, 1912.

Application filed October 3, 1910. Serial No. 585,096.

To all whom it may concern:

Be it known that I, JOSEPH BOERO, a citizen of the Republic of France, and a resident of the city of Paris, in the Department of Seine and Republic of France, have invented certain new and useful Improvements in Disintegrators, of which the following is a specification.

The invention relates to machines adapted to be used for disintegrating materials of various kinds, and is particularly useful for crushing and pulverizing ore as a preliminary to the amalgamating process. Its uses, however, are not limited to this art, and may be extended to many other arts in which it is desired to crush and disintegrate materials of varying degrees of hardness.

The objects of the improvements are, among others, to provide a simple, strong, durable and effective crusher or pulverizer; to reduce the power required to a minimum; to accelerate the operation and do the work more thoroughly, and to accomplish certain other advantages as will appear.

25 The invention consists of the construction, combination and arrangement of parts hereinafter described and claimed and illustrated in the accompanying drawings.

In the drawings, Figure 1 is a perspective view of a disintegrating machine embodying the improvements with the cover removed. Fig. 2 is a vertical medial section taken at right angles to the operating shaft of the device. Fig. 3 is a vertical cross-section substantially on the line 3—3 of Fig. 2, looking in the direction indicated by the arrows.

40 The cover A is provided with an opening A' at its front end near the top, and a hopper B is secured to the edges of this opening and extends above the cover to receive the materials to be crushed which enter the machine through the opening A' of the cover.

45 The cover at its ends has suitable hinge members C by which it is hinged to the lower casing D, hinge members E being secured to the upper edge of said casing. The hinge members C and E have openings C' and D', respectively, bored horizontally therethrough and adapted to receive a rod F, and in this manner when both hinge members are connected, the casing is securely locked, while when the hinge members at one end only are secured, the connection acts as a hinge on which the cover may

be raised and turned back. The raising and lowering of the cover is facilitated by the handles G on either side of the cover.

The shaft H extends between the cover and lower casing, and a suitable recess A² is provided in the cover to receive its bearings J. Suitable bolts K are provided at the ends of the shaft by which it may be connected with suitable power transmitting mechanism.

Inside the casing, and near the inner walls thereof on either side, are a pair of disks L keyed to the shaft H and revolving therewith, and a series of U-shaped beaters M are mounted by having their horizontally turned ends passed into the recesses annularly arranged in the disks. These beaters are not rigidly connected, but are so mounted that they will swing or oscillate on their pivots, and, as will be understood, when the disk revolves they assume the position in which they are shown in Fig. 2. It will also be seen that in striking the material to be disintegrated, these beaters will have a certain amount of annular movement, depending upon the centrifugal force caused by the rapid rotation of the beating mechanism.

55 In the lower part of the casing D a curved screen N is located, and through this screen the crushed material must pass in order to be discharged from the machine.

In the upper part of the cover A are secured blocks R and S extending across the said casing parallel with the shaft and secured thereto by means of bolts R' and S' extending through the top of the cover. The uppermost block R extends a little less than half way across the cover from the end opposite the inlet opening and the lower block extends a little more than half the width of the block R and has its inner edge in proximity to the path of the beaters M, when the beating mechanism revolves (in the direction indicated by the arrow in Fig. 2). When the material enters through the hopper it is struck by one of the beaters and thrown against the block R and broken to pieces. It falls back just in time to be struck by the next succeeding beater which hurls it against the lowermost block and further breaks it. It then falls back within the path of the inner edge of the successive beaters which form a phantom cylinder and is ground to pieces by the attrition of the

moving particles within this phantom cylinder until it is reduced to dust when it falls to the bottom of the cage and through the screen. It will be seen therefore that the crushing of the materials is not accomplished by the impact of the beaters and by contact with the blocks R and S, alone but by violent and rapid contact of the pieces of material with each other inside the cylinder formed by the beaters as they revolve. This is one of the important features of the invention, and provides for the thorough pulverization of the materials at a minimum of power and wear on the parts of the machine.

When the materials are thoroughly crushed they will gradually sift out through the screen N at the bottom, and their place will be taken by fresh materials supplied through the hopper.

In crushing different materials, blocks of different sizes and shapes may be used, and these blocks may be replaced when worn or changed to suit the requirements by simply raising the cover and removing the nuts on the upper ends of the bolts R' and S'.

The operation of the device will be clearly understood from the description of the foregoing.

What I claim is:

A disintegrating apparatus comprising a casing having an inlet opening in the end, a shaft journaled in the casing, beaters mounted on said shaft, a plate secured to the top of the casing and projecting from the end opposite to and projecting toward the opening to a point very near the vertical plane of the shaft, and a second shorter plate directly below the first ending at a point farther away from said vertical plane, and presenting sharp angular corners with which material thrown by the beaters will contact, the angular corner of the upper plate being located at a greater distance beyond the path of movement than that of the lower plate.

Witness my hand, this 8th day of September, 1910, at the city of Paris, Department of Seine, Republic of France.

JOSEPH BOERO.
